RIP STRING ENVELOPE

Willard E. Swift, Worcester, Mass., assignor to
 United States Envelope Company, Springfield,
 Mass., a corporation of Maine

Application November 14, 1931, Serial No. 575,017

5 Claims. (Cl. 229—86)

The present invention relates to that type of envelope which is provided with a rip string, so that one side of the envelope may be quickly and completely opened by a pull on the string to permit ready discharge of the contents of the envelope.

Envelopes embodying the present invention are particularly adapted for the packaging of pulverulent materials, such as individual servings 10 of food, or beverages in powdered form, each envelope being so folded as to effectively prevent leakage of pulverulent material therefrom, with its rip string adapted to cleanly sever one edge, so that the contents may be discharged with a 15 minimum of spilling. The above and other advantageous features of the invention will herein-after more fully appear from the following description with reference to the accompanying drawing, in which:—

20 Fig. 1 is a rear view of an envelope embodying the invention.

Fig. 2 is a plan view of the blank for the envelope.

Fig. 3 is a longitudinal sectional view along the 25 line 3—3 of Fig. 1, showing the envelope filled with pulverulent material, and with the seal flap closed.

Fig. 4 is a transverse sectional view along the line 4—4 of Fig. 3, looking in the direction of the 30 arrows.

Like reference characters refer to like parts in the different figures.

Referring first to Fig. 2, which represents the blank from which the envelope is made, 1 designates the body portion, or front wall of the envelope, 2 designates the back flap, 3 the seal flap and 4, 4 the side flaps, the broken lines bounding the body portion 1 indicating the creases on which the several flaps are to be folded.

40 In forming an envelope from the blank represented in Fig. 2, a length of string 5 is positioned along the intersection between the body 1 and back flap 2, after which the back flap 2 is folded on the broken line 6 into contact with the body 1, 45 thereby loosely holding the string 5 between the body and flap with its ends projecting from opposite sides of the blank. Gum having been applied to the side flaps 4, as indicated at 7, the side flaps are then folded over on the broken lines 8, 50 8 to bring their gummed portions into contact with the outer face of the folded over back flap 2.

At this point it is to be noted that the width of the back flap 2 is somewhat greater than the distance between the lines of folding 8, 8 of the side flaps 4, so that marginal portions of the back flap

2 overlapping the lines 8, 8 are folded over with the side flaps 4, as indicated by the broken lines 8a, 8a. This second folding of the marginal portions of the previously folded back flap 2 results in turning back short lengths of the rip string 5 at the lower corners of the completed envelope, 60 as shown clearly in Fig. 1, thereby holding the string in position, although its intermediate portion along the folding line 6 is not secured to the blank. This double folding of the back flap 2 65 also effectively seals the lower corners of the envelope.

The final step in the formation of the envelope resides in folding over, or scoring, the previously gummed seal flap 3 along the broken line 9, which 70 substantially coincides with the top edge of the folded over back flap 2, the completed envelope then appearing as shown in Fig. 1, with the seal flap 3 turned back. It is to be noted that the junctions of the side flaps 4 with the seal flap 3 75 are located above the line of folding 9, so that when the envelope is closed by turning down the seal flap 3 the upper corners of the envelope are effectively sealed by the double folding of the 80 side flaps 4.

Referring now to Figs. 3 and 4, the sealed envelope is shown as having been filled with a pulverulent material 10; and it is evident that it is 85 practically impossible for the material to escape from the four corners thereof, or along its longitudinal edges, due to the double, or safety, folding of the back flap 2 and side flaps 4 in the manner previously described. Furthermore, while the rip string 5 extends loosely within the bottom 90 edge of the envelope, the pulverulent material 10 cannot escape along the string where it emerges from the sides of the envelope, due to the folding back of the string upon itself at the places where the margins of the back flap 2 are 95 folded with the side flaps 4. This reverse folding of the rip string 5 effectively prevents accidental withdrawal of the string from the envelope, and also presents the projecting string ends so that they may be readily seized for pulling, when it is desired to open the envelope. The 100 initial pull on either end of the string 5 first causes tearing between the overlapped flaps toward one corner of the envelope, after which the string 5 tears the bottom edge of the envelope to completely open the same. Since the tearing of the rip string 5 is only through one thickness of paper, the 105 opening operation can be performed very quickly with one hand while holding the filled envelope body with the other hand in such a posi- 110

tion as to discharge its contents with a minimum of spilling.

I claim,

1. A container or envelope of the class described, comprising front and back walls, side flaps and a flexible rip strand extending along the junction between said front and back walls, said back wall being folded over into engagement with the front wall to loosely enclose said rip strand, and said side flaps, together with marginal portions of said previously folded back wall, being folded over to turn back and secure portions of said rip strand at opposite sides of said container.
- 15 2. A container or envelope of the class described, comprising front and back walls, side flaps and a flexible rip strand extending along the junction between said front and back walls, said back wall being folded over into engagement with the front wall to loosely enclose said rip strand, and said side flaps, together with marginal portions of said previously folded back wall, being folded over to turn back and secure portions of said rip strand at the lower corners of said container with free ends of said strand extending beyond said corners, whereby a pull on either end of said strand will sever the front and back walls along the line of fold therebetween.
- 20 3. A container or envelope of the class de-

30

scribed, comprising front and back walls folded over to loosely enclose a flexible rip strand and side flaps folded over with marginal portions of said back wall to reversely position and retain portions of said rip strand at the lower corners of said container.

10 4. A container or envelope of the class described, comprising front and back walls folded over to loosely enclose a flexible rip strand and side flaps folded over with marginal portions of said back wall to reversely position and retain portions of said rip strand at the lower corners of said container, the double folding of said flaps and said back wall serving to seal the corners of said container and its longitudinal edges against the escape of pulverulent material within the container.

15 5. A container of the class described, comprising front and back walls folded over to loosely enclose a flexible rip strand and side flaps folded over with marginal portions of said back wall to reversely position and retain portions of said rip strand at the lower corners of said container, the double folding of said flaps with the back wall serving to seal the corners of said container to prevent escape of pulverulent material from said container at said corners and along said rip strand.
